UNITED STATES PATENT OFFICE.

LOUIS MATHIEU CHARLES ANICET DUBUC, OF TOULOUSE, FRANCE, ASSIGNOR TO
B. SIRVEN, OF PARIS, FRANCE, A LIMITED JOINT-STOCK COMPANY.

PRINTING MACHINE.

Application filed February 11, 1926, Serial No. 87,649, and in France February 14, 1925.

The present invention relates to various improvements in printing machines, the object of these improvements being specially to avoid the aforesaid inconveniences.

5 These improvements relate firstly to the mechanism for giving the imposing surface of printing machines equal reciprocating movements in opposite directions, and secondly to mechanism for carrying or accompanying the imposing surface to each end of its movements with the object of keeping it in very exact positions.

A printing machine made in accordance with the invention consists essentially in 15 having the driving shaft connected with an intermediate shaft the pinion of which is in mesh with a rack fixed to the imposing surface, the transmission mechanism between these two shafts being such that the said rack acquires alternating rectilinear movements with a constant speed for nearly all the travel of the imposing surface.

The invention also comprises a special 25 form of construction of the aforesaid machine consisting essentially in that the intermediate shaft, carrying a pinion in mesh with the rack of the imposing surface, also carries a pinion interposed between two wheels adapted to be rotated in opposite directions by the driving shaft, these two wheels having teeth only on a part of their exterior circumference (about half their circumference) in such a way that one of the 35 wheels makes the intermediate shaft turn in one direction to produce a forward motion of the rack and imposing surface, this said wheel being then released from the intermediate shaft the pinion of which now meshes with the other half-toothed wheel 40 which drives it in the opposite direction to the preceding movement, and this new movement of the intermediate shaft produces the return movement of the rack and imposing surface.

45 The invention also comprises a printing machine with a mechanism operating at the end of the travel and characterized in that, at the moment when the driving shaft of the imposing surface is not in mesh with 50 either of the two devices for moving the imposing surface in opposite directions, the rack of the imposing surface meshes with a pinion or sector of the same diameter and modulus as the pinion driving the imposing surface and having the same speed as that

of this driving pinion in such a way that the imposing surface continues to move at the same rate of speed.

The invention finally comprises other characteristic features and their different 60 combinations hereinafter described.

A printing machine made in accordance with the invention is shown, by way of example, in the accompanying drawings, in which—

65 Fig. 1 is a plan view of the entire mechanism.

Fig. 2 is a section on line 2, 2, of Fig. 1.

Fig. 3 is a section on line 3, 3 of Fig. 1.

Fig. 4 is a section on line 4, 4 of Fig. 1.

70 Fig. 5 shows partly in section and partly in elevation the device which accompanies or carries the imposing surface at the end of its travel.

Fig. 6 shows a detail of the device shown 75 in Fig. 5.

The mechanism for giving the imposing surface uniform movements in opposite directions, consists of a driving shaft 100 with 80 pulleys 101 and fly-wheel 102; this shaft drives through the agency of a train of spur gears 103, an intermediate shaft 104. This intermediate shaft 104 runs from one side of the machine frame to the other, and on the end opposite its driven end this shaft 85 104 is furnished with a wheel 105 only toothed on a third of its circumference, viz., a sector of 120°.

On this same shaft 104 and by the side of the wheel 105 there is fixed an internally 90 toothed wheel 106 having teeth only on one third of its circumference in a similar way to the wheel 105, viz., on a sector 120°.

The wheels 105 and 106 (see Fig. 3) which 95 are joined together and interdependent alternately and respectively work the pinions 107 and 108 which are also joined together and fixed on the end of an intermediate shaft 110. The diameter of the pitch circle of the wheel 106 is equal to twice the diameter of the pitch circle of the wheel 105. The pitch circle of the pinion 108 is equal to 100 twice the diameter of the pitch circle of the pinion 107.

This ratio between the diameters of the 105 said pitch circles make it possible for the shaft 104 to drive the shaft 110 at the same rate of speed, whether the transmission is by the train of gearing 105, 107 or by the train 106, 108.

At the other end of the intermediate shaft is fixed a pinion 111, of the same diameter as the pinion 108. This pinion 111 works a rack 112 fixed to the imposing surface 113.

5 The aforesaid device works as follows:

In its initial position, the pinion 108 is in mesh with the wheel 106 which turns in the direction 114; therefore the pinion 108 turns in the direction 115. This pinion 108 thus produces parallel motion of the rack 112 and imposing surface 113, in the direction 116.

10 The imposing surface 113 moves forward until the wheel 108 is released from the teeth of the wheel 106; but as the wheel 105 continues to turn in the direction 114, some instants after the pinion 108 is disengaged from the wheel 106, the pinion 107 meshes with the toothed part of wheel 105. Consequently, under the action of the wheel 105 15 the pinion 107 is set in motion in the direction 118.

20 The pinion 111 also turns in the direction 118 to produce movement of the imposing surface 113 in the direction 119.

25 The multiplication ratio of 105 to 107 being the same as that of 106 to 108, we can see that the parallel movements of the imposing surface will be made at the same rate of speed in the directions 116 and 119.

30 Briefly, the mechanism already described makes it possible, by the aid of the driving shaft 100 turning at a speed, constant in rate and direction, to produce rectilinear to and fro motion of the imposing surface 113, each of these movements having a constant speed during the respective periods when the wheels 105, 106 respectively drive the pinions 107, 108.

35 40 It is to be noted that in the device I have described the shaft 110 for driving the imposing surface, becomes free during a very short time when it is no longer in mesh either with the interior toothed wheel 106 or the toothed sector 105; it is therefore necessary that the imposing surface 113 at the end of its travel should be accompanied or carried and kept in very exact positions by means of an end of travel mechanism. This said 45 mechanism must mesh with the imposing surface, a little before the driving shaft 110 of this imposing surface becomes free, in such a way that there is no interruption in the working and movement of this imposing surface, the end of travel mechanism simply taking the place of the driving shaft 110.

50 55 This result can evidently only be attained on condition that the end of travel mechanism, in meshing with the imposing surface, will give it the same rate of speed as its driving shaft 110, otherwise all the machine would be dislocated.

60 65 Finally, the imposing surface must always have the same speed whether driven by its shaft 110 or its end of travel mechanism.

The aforesaid mechanism made according to the present invention permits these difficulties to be overcome. It consists essentially of:

1. A driving crank 120 fixed on the end of the driving shaft 100.

2. A connecting bar 121 guided in slides 122, 123, whereby it moves with a rectilinear motion. This bar 121 has a to and fro motion under the action of the driving crank 120.

3. Two driven cranks 125 which have the essential characteristic of being cranks with arms of variable length; these two cranks are worked from the connecting bar 121 by the aid of a device hereinafter described.

These two cranks 125 are similar and consist of: the crank arm 126 (Fig. 5) formed by a member which can run inside two slides 127, 128 these two said slides, 127, 128, being formed in one with a boss 129 fixed on the end of the shaft 130.

35 The length of the arm 126 is regulated by the displacement of a roller 131, fixed to the rear part of this arm 126.

40 The roller 131 is compelled to run inside a slide 132 (Fig. 6); the portion of this slide 132 within the angle α is cut to the arc of a circle having for its centre the point O on the axis of the shaft 130.

45 From one side to the other of the limits of the angle α the slide is cut to arcs of curvature the convex parts of which face upwards.

50 55 On the front surface of the arm 126, opposite to that which carries the roller 131 is fixed, the shaft 134 of a slide 135 which moves between two guides 127, 128 formed in one with the connecting bar 121.

60 On the shafts 130 are fixed sectors or pinions 138 having the same diameter and modulus as the pinion 111 which drives the imposing surface 113.

65 It will be seen that the rack 112, fixed to the imposing surface 113, will be actuated at the end of every reciprocating movement of the imposing surface, by one or the other of the pinions 138 fixed to the shafts 130.

70 The angle α will be passed over by the roller 131 whilst, the rack 112 being already in mesh with one of the pinions 138, the pinions 107 or 108 are again in mesh with one of the wheels 105 or 106.

75 80 It can easily be seen that during this time the movement of the crank 120 will be strictly in harmony with that of crank 125. Consequently the rotary motion of pinions 138 will be in harmony with that of 111, the time of this synchronism being regulated by the extent of the portion of circular arcs of the slide 132.

85 The aforesaid mechanism works as follows:

90 95 In the initial position the pinion 108 turns in the direction 115 under the action of the

wheel 106 turning in the direction 114. The pinion 108 is no longer in mesh with the last tooth of the wheel 106.

The rack 112 now meshes with one of the pinions 138 rotary motion of which at this instant strictly synchronizes with that of the pinion 111, of the same diameter, as previously explained.

Movement continues and the pinion 108 is released from the last tooth of the wheel 106, the shaft 110 becomes free and the rack 112 is then driven only by the pinion 138 the motion of which is regulated by that of the connecting member 121. But the operation is regulated so that the member 121, under the action of the crank 120, then reaches one of the ends of its travel. Consequently, owing to the form of the slide 132 in which the roller 131 runs, the pinion 138 will slow down in rotation in the direction 115 and come to a stop and start again in the opposite direction 118, (Fig. 1) and also produce a change of direction in the movement of the rack attached to the imposing surface 113 which will start off in the direction 119.

This movement of the rack 112 will cause engagement of the pinion 107 with the wheel 105, at the instant when the first tooth of this wheel 105, which has continued in motion, will mesh with 107.

Thus motion of the shaft 110 is reversed; and this said shaft drives the rack 112 and the imposing surface 113 in a direction opposite to the preceding movement and this brings the imposing surface into its initial position.

What I claim as my invention and desire to secure by Letters Patent is:—

1. In a printing machine the following combination: an imposing surface; a rack fixed to the imposing surface; a driven shaft for the imposing surface; a first pinion fixed to the driving shaft and in mesh with the rack; a second pinion fixed to the driven shaft; an intermediate shaft two wheels only toothed on a part of their circumference, one on the exterior of its rim and the other on the interior, these two said wheels being carried on the intermediate shaft and alternately meshing with the second pinion of the driven shaft in such a way that this driven shaft and consequently the imposing surface acquire movements in the opposite direction according as one or other of the half toothed wheels meshes with second pinion of the driven shaft; a driving shaft, and a transmission device placed between the driving shaft and the intermediate shaft.

2. In a printing machine the following combination: an imposing surface; a rack fixed to the said imposing surface; a driven shaft for this imposing surface; a first pinion fixed to the shaft, and meshing with the rack; two joined pinions fixed to the driven shaft; an intermediate shaft, two wheels

only toothed on part of their circumference, one on the exterior and the other on the interior, these two said wheels being carried on the intermediate shaft and meshing respectively and alternately with the two joined pinions of the driven shaft in such a way that this driven shaft and consequently the imposing surface acquire movements in the opposite direction according as one or other of the half toothed wheels meshes with the corresponding pinion of the driven shaft; a driving shaft; a transmission device placed between this driving shaft and the intermediate shaft.

3. In a printing machine the following combination: an imposing surface; a rack fixed to said imposing surface, a driven shaft for the imposing surface; a pinion fixed to the said shaft and meshing with the rack; a driving shaft; means inserted between the driving shaft and the driven shaft, these said means giving the driven shaft and consequently the imposing surface to and fro movements; two end of travel pinions of the same diameter and modulus as the driving pinion of the imposing surface, these pinions being placed at the two extremities of the machine so as to mesh at the end of travel with the rack of the imposing surface and driving means giving these two pinions rates of speed equivalent to those of the driving pinion.

4. In a printing machine the following combination: an imposing surface; a rack fixed to said imposing surface; a driven shaft for the imposing surface; a pinion fixed to the said shaft and meshing with the rack; a driving shaft; means inserted between the driving shaft and the driven shaft, these said means giving the driven shaft and consequently the imposing surface to and fro motions; two end of travel pinions of the same diameter and modulus as the pinion for working the imposing surface these said pinions being placed at the two extremities of the machine so as to mesh at the end of travel with the rack of the imposing surface; two cranks of variable length fixed respectively on the two end of travel pinions a crank with an invariable length fixed on the driving shaft; means connecting the pins of these cranks; means for modifying the length of the two cranks of the two end of travel pinions, in such a way that the variations in the length of these cranks compensates for the differences in linear speeds produced by working the driving shaft with the crank and thus finally enables the same speed to be obtained on the end of travel pinions as that on the pinion working the imposing surface.

5. In a printing machine the following combination: an imposing surface; a rack fixed to said imposing surface; a driven shaft for the imposing surface; a pinion

fixed on the said shaft and meshing with the rack; a driving shaft; means interposed between the driving shaft and the driven shaft these said means giving the driven shaft and consequently the imposing surface to and fro movements; two end of travel pinions of the same diameter and modulus as the pinion for driving the imposing surface, these said pinions being placed at the two ⁵ extremities of the machine so as to mesh at the end of travel with the rack of the impos-

ing surface; two cranks of variable length fixed respectively on the two end of travel pinions, each of these cranks consisting of a sliding part engaged in an eccentric slide of the frame; thus producing an automatic variation in length of the crank during its rotations; a crank of invariable length fixed on the driving shaft and means connecting the pins of these cranks. ¹⁵

In testimony whereof I affix my signature.
